NEW YORK

ELECTRIC LAMP RECEPTACLE

Application filed November 30, 1925. Serial No. 72,241.

This invention relates to electric lamp receptacles and more particularly to wall or ceiling fixtures.

It is a general object of the present invention to provide a novel and improved type of electric fixture.

More particularly it is an object of this invention to provide an electric fixture, for use on walls or ceilings, having a canopy 10 which is held in position against the wall or ceiling solely by means of a ring engaging the screw shell of the lamp socket forming a part of the fixture.

Another object of the present invention 15 consists in the provision of an insulating shade ring adapted to have threaded engagement with the exterior of the screw shell of a lamp socket.

A further object of the present invention 20 consists in the provision of an electric fixture provided with a socket adapted to be adjustably secured to any of the well-known types of conduit boxes; a canopy to enclose the base of this socket placed against the 25 wall supporting the conduit box; and a shade ring engaging the screw shell of the socket and holding the canopy in position.

A still further object of the present invention consists in the provision of interlocking means between a socket supported 30 from a conduit box and a canopy to prevent relative rotation between the same.

Still another object of the present invention consists in the provision of an insulating shade ring having threaded engagement 35 with the exterior of the screw shell of a socket which is adjustably supported from a wall or ceiling and serving as the sole means to retain a canopy in position over the base of the socket.

Other and further objects of the present invention will be more apparent as the description proceeds.

For a complete understanding of the present invention reference should be had to the 45 accompanying drawings and following specification, wherein are disclosed several exemplary embodiments of the present invention, with the understanding, however, that various changes may be made therein by

those skilled in the art without departing from the spirit of the invention, or the scope of the appended claims.

In said drawings:

Figure 1 is an elevation of an electric fixture, constructed according to the present invention, shown secured in position on a conduit box, the wall supporting the conduit box being shown in section;

Figure 2 is a plan view of the fixture shown in Figure 1 with the lamp and shade removed;

Figure 3 is a longitudinal central section through the fixture disclosed in Figure 1, certain parts being shown in elevation;

Figure 4 is a bottom plan view of the socket adapted for use with the receptacle;

Figure 5 is a view similar to Figure 3 but showing the fixture mounted upon a different type of conduit or outlet box and being 70 provided with a lamp ring instead of a shade ring; and

Figure 6 is a view similar to Figure 3 showing the fixture with still a different type of conduit box.

The present invention contemplates the provision on an electric fixture preferably formed with all of the exposed parts of insulating material such as molded porcelain, bakelite or the like. Such a type of fixture, 80 especially when made in white porcelain, is very desirable for use in bath rooms, kitchens and like places where the smooth white surface offers but slight lodgment for dust and can readily be cleaned with a damp 85 cloth.

Referring to Figures 1 and 2, it will be seen that the fixture is adapted to be supported from a conduit or outlet box of any of the well-known types, such as 10, which is 90 secured to or fastened in a wall 11 in any conventional manner. The main visible portion of the fixture is the canopy 12 of generally frustro-conical form, although any desired shape to conform to the surrounding furnishings may be used. The large end of the canopy 12 is provided with a flat base 13 adapted to fit closely against the wall and hide from view the conduit box. A shade ring 14 is secured to the fixture in a manner 100

to be later described and provides means for the attachment of a shade 15 of glass or china such as are well-known in the art and which serves to diffuse and soften the light from the lamp 16 mounted axially in the fixture. 5 The fixture may be mounted either on a wall or the ceiling and is conveniently provided with a pull chain 17 for lighting and extinguishing the lamp, although where wall 10 switches are used the fixture can be readily formed with a keyless socket and the chain eliminated.

Considering first the construction disclosed in Figure 3, it will be seen that the outlet box 10 is of any suitable form and is mounted with its outer surface substantially flush with the surface of the wall upon which the fixture is to be mounted. The socket or lamp receiving element of the fixture comprises a porcelain base 18 of the form shown in Figures 3 and 4 upon the upper face of which is mounted the screw shell 19 internally and externally threaded as is common in most sockets. The usual center contact 20 is also provided. Within a recess in the bottom of the porcelain base 18 is arranged a conventional form of pull chain switch covered by a sheet of insulating material 21. This switch may be of any convenient type, 25 and since it forms no part of the present invention, has not been shown in detail and will not be further described. In case the fixture is intended for use with a wall switch, the base 18 will be of the same configuration 30 but will be solid instead of apertured to receive a switch. The ears 22 of the base are perforated as at 23 to receive the screws 24 which are not threaded in the portion passing through these ears. Between the unthreaded and the threaded portions of each 35 screw is arranged a crimped washer or like device 25 to retain the screw in position loosely in the base so that it will not be lost in shipment. Preferably lock washers 26 are provided beneath the heads of the screws.

A mounting strap 27 is provided for the socket which strap comprises a stamping or punching of sheet metal having the ears 28 provided with the threaded openings 29 adapted to be engaged by the screws 24 for 40 adjustably positioning the mounting strap in relation to the socket base. The central portion 30 of the mounting strap lies in a plane parallel to but spaced a considerable distance 45 from the plane of the ears 28 and is provided with the large central aperture 31 and the radial slots 32 connected therewith. The outlet box 10 may be provided with a box strap 33 which extends diametrically across 50 the face of the box and is secured to the usual ears thereon by the screws 34. Near its center this box strap is perforated to receive and threadedly engage the screws 35 which pass through the portion 30 of the mounting strap 55 and are engaged in the slots 32 therein to thus

enable the mounting strap to be securely fastened to the box strap, thereby securing the base of the socket to the outlet box in such a manner that it can be adjusted to and from the same by rotation of the screws 24. 70

The canopy 12 is hollow, as best shown in Figure 3, and as its outer end is provided with the aperture 36 so that it can readily be placed over the socket base after the same has been mounted on the outlet box with the screw shell 19 projecting through the aperture 36 and entirely beyond the outermost portion of the canopy. 75

The fixture is wired by bringing conductors from the conduit box to the circuit terminals 37 of the socket before the canopy is placed in position. The canopy is then mounted over the socket base and the shade ring 14 applied to hold it in position. This shade ring is formed preferably by molding from the same or similar material used in making the canopy and has a central aperture 39 threaded to engage over the external threads of the screw shell 19. The inner flat annular surface 40 of the shade ring 14 engages the outer flat annular surface 41 of the canopy so that when the ring is screwed into position it presses the canopy tightly against the wall 11 to retain it in position without the aid of other fastening means such as screws and the like which are usually resorted to. 80 85 90 95

The unique construction of the shade ring 14 is an important feature of the present invention. Being formed entirely of insulating material it can be threaded directly upon the screw shell of the socket and forms not only a finish for the same but a mechanical and electrical protection therefor. The exterior of the shade ring may be of any desired configuration to carry out the motif of the canopy and is provided with a circumferential flange 42 having an inner cylindrical surface 43 of a size to receive the base of the usual shade such as shown in Figure 1. This flange is provided with a plurality, preferably three, substantially radial perforations adapted to receive therein tubes 44 which are internally threaded to be engaged by the screws 45 used in the well-known manner to retain the shade in position. The apertures are counterbored at the exterior of the flange to allow the tubes to be headed over to retain them in position. At the inner ends of the apertures, the flange is provided with the recesses 46 to receive the large non-circular heads on the tubes 44 so that the edges of the heads may engage the walls of the recesses and thereby hold the tubes against rotation. 100 105 110 115 120 125

In order that there shall be no relative rotation between the canopy and the socket base, the interior of the canopy is so shaped as to receive the ears 22 of the socket base in recesses 47 in the walls of the canopy, which recesses are so shaped that their walls engage with the edges of the ears and thus 130

prevent rotation. This engagement of the ears in the recesses serves another purpose, for it locates the switch base within the canopy in such a manner that the pull chain leaves the switch at the proper angle and passes through the aperture 48 provided in the canopy for the same, thus insuring that there be no binding in the action of the chain.

In initially mounting a fixture of the type 10 just described, the box strap 33 is so secured upon the box as to allow the proper positioning of the mounting strap 27 thereon, by means of the screws 35 being placed in any of the slots 32, so that the chain will hang in the proper position when the fixture is mounted. Then by the aid of a suitable template or other measuring device the screws 24 are adjusted until the top face of the ears 22 is a sufficient distance from the wall to allow 20 the major portion of the screw shell 19 to project through the opening 36 in the canopy, and yet not so far as to have the top faces of the ears 22 engage against the bottoms of the recesses 47 and thus hold the canopy away 25 from the wall.

The above described arrangement allows for the ready removal of both the shade ring and the canopy without disturbing the wiring, for the purpose of inspecting or changing the same. Also the washable parts of the fixture can be removed by a novice and replaced after cleaning without disturbing the wiring.

In order that vibrations or other extraneous means may not cause the shade ring to become unscrewed, it is preferred to provide it with a counterbore 49 which is provided in its cylindrical wall with teeth or longitudinal flutes 50, as shown in Figure 3, 30 which are adapted to be engaged by a spring finger 51 secured, in any desired manner, to the switch base and projecting up alongside of and substantially parallel to the screw shell. The circular opening 36 in the top 40 of the canopy has a connecting radial slot 52 extending therefrom to allow this spring finger to pass freely through the same. The outer face of the spring finger may be provided with a punched out projection to fit 50 between the teeth in the counterbore and offer resistance to the unscrewing of the shade ring. At the same time the slot 52 limits the mounting of the base within the canopy to a single position, whereas the recesses 47 only 55 limit the assembly of the socket within the canopy to two positions. This absolutely insures the proper positioning of the chain.

The adjustable feature provided by the screws 24 passing through the mounting strap 27 allows for considerable variation in the positioning of the conduit box. It is well-known that in building construction the boxes are mounted before the walls are plastered or otherwise finished, and the boxes may 60 be crooked, project above the plaster or be

considerably sunken below the same, but nevertheless the adjustability of the screws taken together with their looseness in the ears of the socket base allows for compensation of these inequalities in the box mounting.

The construction disclosed in Figure 5 is substantially identical with that shown in Figure 3 but a different type of box is used. The box 10' is mounted back of the plaster 70 11 and is provided with a cover or neckpiece 60 projecting through the wall in such a form that a box strap cannot be arranged on the box. In this case the usual form of fixture stud 61 may be secured in the bottom of the box as is well-known by means of bolts 62. Upon this fixture stud is mounted the extension adapter 63 which has a bottom portion 64 perforated to fit over the stud. This portion 64 is retained in position by the nut 65 threaded upon the fixture stud in the usual manner. The portions 66 project at a right angle to the base 64 of the extension adapter and are connected at their upper ends and provided with the right-angled ear 67 threaded to receive the screws 68 which pass through 80 the slots 32 in the widened portion of the mounting strap 27 secured to the socket base. In this wise the socket base is rigidly secured to the conduit box 10' and the canopy and shade ring can be mounted as previously described.

In case it is not desirable to use a shade with the fixture, the shade ring may be replaced by a lamp ring 69, shown in Figure 5, which is substantially identical with the 100 shade ring but instead of having the flange 42 provided with the shade screws 45, it merely has an outer surface 70 conforming to a portion of a sphere so that a spherical or globular lamp may be used which fits closely 105 down to the surface 70 and thus makes a neat finish.

In Figure 6 the fixture is disclosed as mounted upon a BX or surface type of box 10², in which case the mounting strap 27 has its large central aperture 31 mounted directly 110 upon the stud 71 of the box 10² and held thereon by the lock nut 72. In this case as well as in the case of Figure 5, the adjustability of the mounting strap to and from the 115 socket base is of extreme importance in order to enable the proper assembly and mounting of the fixture irrespective of the exact positioning of the boxes or slight variations in their size due to being made by different 120 manufacturers.

Various other means of mounting the fixture will suggest themselves to those skilled in the art, but it is considered that the essential feature resides in the adjustability of the mounting strap as previously described.

Having thus described the invention what is claimed as new and desired to be secured by Letters Patent is:

1. In an electric fixture, in combination,

- a socket structure, an insulating base therefor, a screw shell mounted on said base, a mounting strap, screws passing thru said insulating base and loosely and adjustably securing said mounting strap thereto, said mounting strap being adapted to be secured to any type of conduit box mounted on a wall, a canopy adapted to fit over said socket base and against the mounting of said conduit box, said screw shell passing thru said canopy, and an insulating shade ring having threaded engagement with said screw shell to press said canopy against said mounting.
2. In an electric fixture, in combination, an insulating socket base, ears thereon, screws passing freely thru said ears, means to retain said screws in said ears, a mounting strap engaged by said screws for adjustment to and from said base, means securing said strap to an outlet box, a screw shell secured to said base, a canopy adapted to fit over said base with the screw shell projecting thru an aperture therein, said canopy having recesses to receive said ears to prevent relative rotation between said socket base and canopy and an insulating shade ring having threaded engagement with said screw shell and abutting the outer face of said canopy to hold said parts together and said canopy against the wall supporting said outlet box.
3. In an electric fixture, in combination, an insulating socket base, a screw shell secured thereto, a canopy having an aperture to allow said screw shell to project thru the wall of said canopy, a spring secured to said base and projecting thru said aperture, an insulating ring having threaded engagement with said screw shell and means on said ring to engage said spring to prevent the ring from unscrewing.
4. In an electric fixture, in combination, an insulating socket base, ears thereon, screws passing freely through said ears, mounting means adapted to be secured to an outlet box, said screws engaging in said means to adjust said base in respect thereto, a screw shell secured to said base, a canopy adapted to fit over said base with the screw shell projecting through an aperture therein, said canopy having a recess to receive one of said ears and a ring threaded on said screw shell and engaging the canopy to hold the same against the wall supporting said outlet box.
5. In an electric fixture, in combination, a lamp receptacle having an insulating base, a screw shell and a pull chain switch mechanism; fastening means permanently attached to said base for adjustably securing the receptacle non-rotatively to a mount, a canopy adapted to fit over said base and have its edge rest on a wall, said canopy having an aperture to permit the passage of the receptacle screw shell therethrough and a hole for the passage of the pull chain, means on said base and canopy cooperating in but one position to align the hole and chain and a ring of insulating material threaded over said screw shell to hold the canopy against said wall.
6. In a lamp socket, in combination, a base, a screw shell contact thereon having exterior threads, and interior threads to receive and electrically connect a lamp base, a shade holder of insulating material having a bore, threads on the wall of said bore directly engaging the exterior threads of said screw shell, a circumferential flange projecting from said shade holder adapted to surround the base of a shade and means carried by said flange to project inwardly and engage the shade base to clamp it in position.
- In testimony whereof we hereunto affix our signatures.
